[57] **CLAIM**

The ornamental design for a flexible scrubber guard, as shown and described.

DESCRIPTION

FIG. 1 is perspective view of a flexible scrubber guard showing my new design in a fully relaxed position;
FIG. 2 is a side view of thereof;
FIG. 3 is a top view of thereof;
FIG. 4 is an enlarged sectional view taken along line 4—4 of FIG. 1.
FIG. 5 is a bottom view thereof; and,
FIG. 6 is a top view of the flexible scrubber guard showing an oval shape the guard commonly assumes when in use.

FIG. 1

FIG. 4

FIG. 2

FIG. 3

FIG. 5

FIG. 6
